BY Meyers & Jones
ATTORNEYS.

UNITED STATES PATENT OFFICE

JOSEPH ROSENBLUTH, OF CAMDEN, NEW JERSEY, ASSIGNOR TO AMERICAN CIGAR COMPANY, OF NEW YORK, N. Y., A CORPORATION OF NEW JERSEY

GUARD FOR CIGAR MAKERS' BENCHES

Application filed December 17, 1930. Serial No. 503,092.

My present invention relates to cigar makers' benches or tables and more particularly to a means associated with such benches or tables to prevent and at all times serve as a constant reminder to cigar makers or finishers against employing the unsanitary practice of placing the cigars to his or her lips, or wetting the fingers by placing them to the lips in or during the cigar finishing operation.

It is well known in the cigar making industry that in some factories the cigar makers as well as the finishers of machine-made cigars employ the unsanitary practice above referred to and which is not only frowned upon but positively forbidden in certain factories. It is the object of the present invention to provide a simple and easily applied means to obviate the said practice.

The means forming the subject-matter of the present invention may be applied to cigar makers' benches or tables or to the benches or tables attached to and usually forming a part of a cigar making machine, these tables being located at the discharge or finishing end of the machine.

Broadly considered the invention comprises a cigar maker's or finisher's bench or table having a guard or barrier arranged at the front thereof and sufficiently elevated to give the operator ample room or freedom in the use of his or her hands in the performance of the necessary cigar making or finishing operations, while at the same time said guard or barrier is so positioned that when the operator is seated at the bench or table in the usual position for operation an attempt to raise his or her hand to the mouth will bring the hand into direct contact with the guard or barrier which thus serves to prevent and at all times act as a constant reminder to the operator that the cigar being made or finished is not to be brought into contact with his or her mouth.

In the accompanying drawings wherein I have illustrated two types of means for accomplishing the objects of the invention, Figure 1 is a perspective view of a cigar maker's bench or table having one form of guard or barrier connected therewith.

Figure 2 is a perspective view of a slightly modified form of the invention, and

Figure 3 is a section of a portion of the guard or barrier taken on the lines 3—3 of Figure 2.

In the embodiment of the invention illustrated in Figure 1, the reference numeral 1 indicates an ordinary cigar maker's or finisher's bench or table at which the operator sits on a stool or chair 2. The numeral 3 indicates an ordinary cutting block with which these benches or tables are usually provided and upon which the operator places an unattached portion of the cigar wrapper at the head end of the cigar in order to trim said unattached portion preparatory to winding it about the cigar head in the finishing operation. The numeral 4 indicates a paste receptacle which contains the paste employed in attaching the final end of the wrapper to the cigar head. These cigar makers' benches or tables are also usually provided with a rotary cigar head finishing tool (not shown) which tool is usually provided with a conical wall to apply a final finishing pressure to the somewhat conical end of the cigar head. All of these features are common and well known in the art.

In order to prevent and make it difficult and to at all times serve as a reminder that the operator must not bring the cigar to his or her lips in performing the finishing operations, I have provided the bench or table with an elevated barrier or guard, which in the form of the invention illustrated in Figure 1 consists of a bar or rod 5 secured at its ends to uprights 6 which latter are secured to the bench or table in any suitable manner as by screws 7 passed through laterally bent portions 8 of the uprights 6. The guard or barrier 5 is of such a length and the uprights 6 are so positioned near the front edge of the bench or table, and at such a height above the table, that there is ample room below the barrier for freedom of use of the hands of the operator in performing the cigar making or finishing operations, while at the same time the said barrier is so located that any attempt of the operator to raise his or her hand to the mouth will cause

the hand to come into contact with the barrier and thus prevent and forcibly remind the operator that the cigar being operated upon must not come into contact with his 5 or her lips.

In the form of guard or barrier illustrated in Figure 1, I have also provided a glass panel 9 through which the operator may easily see the work as it is being performed, said panel 10 being supported at its ends by rearwardly and upwardly inclined extensions 10 formed integral with the uprights 6. It is understood that the glass panel 9 is not a necessary part of the invention and may be used or 15 not, as desired, but when used it serves as a further means for preventing the operator from raising his or her hands to the mouth.

In that form of the invention illustrated in Figure 2 the barrier or guard is in the 20 form of two parallel rods 5a which are secured at their ends in any suitable way to the uprights 6a, the uprights in this form of the invention consisting of metal plates each having its lower end bent laterally as 25 at 8a and secured to the bench or table 1a by means of screws 7a. The ends of the barrier rods 5a may be secured to the upper ends of the uprights 6a by solder or by welding the same to inturned portions 9a at the upper 30 ends of the said uprights.

It is to be understood that my improved guard or barrier may be attached to a cigar maker's bench or table or to the bench or table forming a part of the finishing end of 35 a cigar making machine and in view of its simplicity and ease of attachment it adds practically no cost to the bench or table, yet it admirably fulfills the purposes for which it is intended.

40 What I claim is:—

1. A cigar maker's or finisher's bench or table having an elevated guard or barrier arranged transversely thereof and positioned near its front end, for the purpose specified, 45 the character of the guard or barrier and its elevated position relative to the bench or table being such that the vision and freedom of movement of the hands of the operator except in an upward direction are not unduly 50 restricted.

2. A cigar finisher's bench or table having an elevated guard or barrier arranged transversely thereof and means for positioning the same near the front end of the bench or 55 table comprising uprights to which the guard or barrier is attached, the character of the guard or barrier and its elevated position relative to the bench or table being such that the vision and freedom of movement of the hands of the operator except in an upward direction are not unduly restricted.

3. A cigar finisher's bench or table having an elevated guard or barrier arranged transversely thereof and positioned near its front 60 end and including a transparent panel, the

character of the guard or barrier and its elevated position relative to the bench or table being such that the vision and freedom of movement of the hands of the operator except in an upward direction are not unduly 70 restricted.

4. A cigar finisher's bench having an elevated barrier including a transparent panel, and uprights attached to the bench at opposite sides thereof near its front upon which 75 the barrier is mounted, the character of the guard or barrier and its elevated position relative to the bench or table being such that the vision and freedom of movement of the hands of the operator except in an upward 80 direction are not unduly restricted.

5. A cigar finisher's bench having an elevated barrier including an upwardly and rearwardly inclined transparent panel, and uprights at opposite sides of the bench for supporting the barrier above the table near 85 its front edges, for the purpose specified.

6. A guard or barrier for attachment to a cigar finisher's bench, comprising a transverse bar or rod of approximately the length 90 of the bench with which it is to be used, and spaced uprights to the upper ends of which the opposite ends of the bar or rod are to be attached and means at the lower end of the uprights for attaching them in position. 95

Signed at New York in the county of New York and State of N. Y., this 12 day of December, A. D. 1930.

JOSEPH ROSENBLUTH.
